[21] Appl. No.: 724,330

CLAIM

[22] Filed: Jul. 1, 1991

The ornamental design for a wheel cover exterior sur-
face for a lift truck, as shown and described.

[52] U.S. Cl. D12/204

DESCRIPTION

[58] Field of Search D12/204, 209, 210, 211,
D12/212, 135; 301/37 R, 37 P, 63 R, 63 PW,
64, 65

FIG. 1 is a perspective view of a wheel cover exterior
surface for a lift truck showing my new design; and,
FIG. 2 is an enlarged front elevation view thereof.
The broken line showing an environmental structure in
a drawing is for illustrative purposes and forms no part
of the claimed design.
